UNITED STATES PATENT OFFICE.

WILLIAM W. MACFARLANE, OF PHILADELPHIA, PENNSYLVANIA.

TRANSLATING DEVICE.

1,367,613.

Specification of Letters Patent.

Patented Feb. 8, 1921.

Application filed November 22, 1917. Serial No. 203,379.

To all whom it may concern:

Be it known that I, WILLIAM W. MACFARLANE, a citizen of the United States of America, and a resident of Philadelphia, in the county of Philadelphia and State of Pennsylvania, have invented a certain new and useful Translating Device, of which the following is a specification.

The present invention relates generally to translating devices or induction coils and has more particularly reference to a device of such low resistance that a relatively large volume of current may be passed through it to create a relatively powerful effect even though the current be of low voltage.

The convolutions of the windings receiving the current must have a relatively large cross section, say, one-eighth or three-eighths of an inch so that there may be as little resistance as possible to the flow. To accomplish this, a very heavy conductor must be employed. Therefore, more than a single layer of convolutions is inconvenient and this limits the number of ampere turns.

The principal feature of the invention resides in the use of a plurality of helices, the convolutions of which are of relatively large cross sectional area and in so combining them that a great number of ampere turns, without increase of the resistance of the translating device, is possible. This is effected by connecting a plurality of helices or coils in parallel each having a core and the cores of the various coils being preferably connected to a unitary pole-piece so as to concentrate the magnetic flux.

Another feature of the invention consists of an induction coil having a plurality of windings or helices connected in parallel and a winding in inductive relation to the plurality of parallel windings.

Other features of invention will appear as the specification proceeds.

In the drawings:

Figure 1 is a view partly in elevation and partly in section of a translating device or induction coil embodying the invention.

Fig. 2 is a vertical sectional view on the line 2—2 of Fig. 1.

Fig. 3 is a view partly in elevation and partly in section of one of a group of helices employed.

Fig. 4 is a sectional view on the line 4—4 of Fig. 3.

1 indicates a helix of good conducting material, preferably formed by cutting a spiral

groove in a bar to provide convolutions, the adjacent convolutions being separated by an air gap that may act as insulation. After the spiral groove is cut in the bar, the central portion is entirely removed so as to admit of the introduction of a core 2 surrounded by an insulation sleeve 3. A plurality of these helices are introduced through openings in the standards 4 so as to form a group of parallel coils. The standards 4 may, and in the present instance do, act as conductors by means of which current is introduced into the helices 1 that are, when mounted in the standards, electrically connected thereto. The ends of cores 2 project beyond standards 4 and are provided with a unitary pole-piece 5 that serves to concentrate the magnetic flux. It will be understood that the device so far described is an electro-magnet and may be used to operate one or more armatures 6 to close and open a circuit at contact 7.

A winding 8 is placed around the group of helices, when the device is to be used as a low resistance winding of an induction coil, thereby bringing it in inductive relation to the helices.

By the means shown, a relatively large current, which may be of relatively low voltage may be passed through the helices. It may then, by the means described, be transformed into a current of relatively small volume and relatively high voltage.

The device has been found exceedingly useful in telephone systems, train control systems, etc.

I claim:

1. A translating device including: a plurality of coils, each coil consisting of a single layer of convolutions, two terminal members common to all the coils and to which said coils are electrically connected in parallel, a core for each coil insulated therefrom, and means for concentrating the magnetic flux of said cores.

2. A translating device including: a plurality of coils electrically connected in parallel, each coil consisting of a single layer of convolutions of relatively large cross section and of low resistance, a core for each coil, and means for concentrating the magnetic flux of the cores.

3. A translating device including: a plurality of naked coils insulated from each other by an air gap, each coil consisting of a single layer of convolutions, adjacent con-

volutions being separated from each other by an air gap, and means electrically connecting said coils in parallel.

4. A translating device including: a plurality of naked coils insulated from each other by an air gap, each coil consisting of a single layer of convolutions, adjacent convolutions being separated from each other by an air gap, means electrically connecting 10 said coils in parallel, a core for each coil, and means for concentrating the magnetic flux of said cores.

5. An electromagnet including: a plurality of separate coils, a supporting member for each end of the coils, said supporting members serving also as common terminal conducting members for the plurality of coils, and a core for each of said coils extending through said terminal supporting 20 members and insulated therefrom.

6. An electromagnet including: a plurality of separate coils, a supporting member for each end of the coils, said supporting members serving also as common terminal conducting members for the plurality of coils, a core for each of said coils extending 25 through said terminal conducting members and insulated therefrom, and a pole piece common to all the cores, said cores being 30 joined to said pole pieces.

7. A translating device comprising: a plurality of parallel cores, a winding for each core, the several windings being electrically connected in parallel, and a winding surrounding all the cores and in inductive relation to the individual windings thereof. 35

8. A translating device comprising: a plurality of parallel cores, a winding for each core, and a winding surrounding all the cores and in inductive relation to the individual windings thereof. 40

9. A translating device comprising: a plurality of coils, each coil consisting of a single layer of convolutions extending around a separate core, the several coils being electrically connected in parallel, and a winding surrounding all the coils and in inductive relation thereto. 45

10. A translating device comprising: a plurality of coils, each coil consisting of a single layer of convolutions of relatively large cross-sectional area and of low resistance extending around a separate core, the several coils being electrically connected 50 in parallel, and a winding surrounding all the coils and in inductive relation thereto. 55

Signed at Moncton, in the Province of New Brunswick, Dominion of Canada, this 19th day of November, 1917.

WILLIAM W. MACFARLANE.
